Filed Mar. 9, 1959, Ser. No. 54,906

Term of patent 14 years

(Cl. D81—10)

FIG.1.

FIG.2.

FIG.3.

Figure 1 is a top plan view of a gas burner showing my new design.

Figure 2 is a side elevational view of the gas burner shown in Figure 1.

Figure 3 is a vertical sectional view taken substantially on the line 3—3 of Figure 1.

The characteristic features of my design reside in the portions shown by means of full lines in the drawing.

I claim:

The ornamental design for a gas burner, substantially as shown and described.
